[57] CLAIM

The ornamental design for a tiered lid for kitchenware item, such as coffee maker, as shown and described.

DESCRIPTION

FIG. 1 is a perspective view of a tiered lid for kitchenware item, such as coffee maker showing my new design; FIG. 2 is a perspective view thereof, with the knob of the lid in a down position;

FIG. 3 is the perspective view thereof of FIG. 2, with the knob of the lid in a raised position;

FIG. 4 is a side elevational view thereof, all sides being the same;

FIG. 5 is a top plan view thereof; and,

FIG. 6 is a bottom plan view thereof.

The broken line showing of a coffeemaker base is for illustrative purposes only and forms no part of the claimed design.
